4 SHEETS—SHEET 4.

This technical drawing illustrates a mechanical system for lifting a load. The top part shows a vertical frame with a large wheel at the top. A horizontal beam labeled 'Load' is suspended from the frame. A vertical rod labeled '2' is attached to the frame and the beam. A pulley system is shown on the left, with a wheel labeled '10' and a vertical rod labeled '24'. A horizontal rod labeled '22' is attached to the frame and the pulley system. A vertical rod labeled '2' is also attached to the pulley system. The bottom part shows a side view of the system, including a wheel labeled '26' and a vertical rod labeled '1'.

Inventor:

Combs, Atty.

UNITED STATES PATENT OFFICE.

WILLIAM S. OVERLIN, OF COLLINS VIEW, OREGON.

TRUCK.

1,289,529.

Specification of Letters Patent. Patented Dec. 31, 1918.

Application filed December 22, 1917. Serial No. 208,393.

To all whom it may concern:

Be it known that I, WILLIAM S. OVERLIN, a citizen of the United States, residing at Collins View, in the county of Multnomah 5 and State of Oregon, have invented new and useful Improvements in Trucks, of which the following is a specification.

This invention relates to trucks for handling heavy and bulky articles, such as piles 10 of lumber for example, and consists in improvements in the construction of the body or frame and of the running gear, in the means for picking up the load, and in the mechanism for operating said means. The 15 truck, in its preferred form and as herein illustrated, is a motor truck, and the hoisting mechanism is operated by the same motor which drives the rear wheels.

In the accompanying drawing, 20 Figure 1 is a side elevation of a motor lumber truck embodying my invention.

Fig. 2 is a perspective view of the frame.

Fig. 3 is a vertical section through one of the vertical frame members.

25 Fig. 4 is a horizontal section through said member on line 4—4 of Fig. 3.

Fig. 5 is a perspective of one of the load engaging shoes.

Fig. 6 is a side elevation of another form 30 of shoe, and

Fig. 7 is a side view of another form of truck.

The frame is of the type which enables the truck to be run over the lumber pile, or other 35 load to be transported, and consists of two rolled iron beams of standard section, preferably I beams, bent into inverted U-shape, the legs 2 standing vertically at the four corners of the truck and the curved portions 40 3 forming arches across the front and rear of the truck. Longitudinal beams 4 and 5 join the vertical members near their top and bottom respectively.

The frame thus constructed is supported 45 on the wheels 1 through springs 6 carried by the vertical frame members. The ends of the spring are connected to the flanges of a T-iron 7, secured to the upper part of the leg 2 by pieces of sheet metal 8 welded to 50 the flanges of the leg beam and to the web and flange of the T-iron.

A socket-piece 9 is secured to the spring-

clip 10 and receives and rests on the top of a rod 11, which passes through bearing blocks 12 secured between the outer flanges 55 of the leg beam. Near its lower end said rod carries the wheel spindle 13, the outer end of which is supported in a bracket 14 secured to said rod and pivotally connected by a link 15 to a bracket 16 projecting from 60 the longitudinal member 5. The links 15 and brackets 16 are omitted in the case of the spindles 13 of the front wheels, leaving their rods 11 free to be turned in steering. The brackets 14 are removed in Fig. 1 and 65 from the front wheel spindle in Fig. 2.

Each bracket 16 also supports the outer end of a spindle 17, on which is a sprocket wheel 18 which drives, by chain 19, a sprocket wheel 18' carried by the rear wheel 1.

In practice, the invention is embodied in a motor truck, although this is not essential to the features just described; 20 represents the motor, 21 the casing inclosing the driving shaft and differential, the shaft 22 of 75 which carries a sprocket wheel 23, the chain 24 of which drives a sprocket wheel 25 secured to the wheel 18. 26 is the steering rod and 27 the links by which it is connected to the spindles 11 of the front wheels.

80 There remains to be described the means by which the load is lifted and supported in transit. This consists of shoes or lifting plates which are slidably mounted between the inner flanges of the lower ends of the 85 leg beam 2, angle irons 29 being secured to said flanges and bars 30 at the angles of the same with the web of the beam to form guideways for the vertical members of said shoes to slide in.

90 Each shoe consists, as shown in Figs. 2 to 5, of an upper plate 31 and a lower plate 32, hinged together at 33, plate 32 carrying the lifting shelf 34. The backs of said plates carry lugs 35 connected by a spring 36 tending to swing the plate 32 on the hinge when in its lowermost position, as indicated in dotted lines in Figs. 2 and 3. Plate 32 has a beveled rib 37 on its back which contacts with the web of the leg beam. Plate 31 has a sheave 38 mounted on its back, around which passes a cable 39, one end of which is secured at 40 to said web. Fig. 6 shows a 100 simpler form of shoe, consisting of lifting

shelf 34 and one vertical plate 41, carrying the sheave 38. To maintain said plate in its position flush with the edges of the flanges of the leg beam, it is provided with a plurality of studs 42 on its back. The cable 39 from each shoe passes over a guide sheave 43 to a winding drum 44, to which its end is attached; that from the front shoe passes around said drum in the opposite direction to that from the rear shoe. The same arrangement is duplicated on the other side of the machine, the two drums 44 and each pair of idlers being on common shafts 45 and 46 respectively. Drum shaft 45 also carries a gear 47 and a brake disk 48, the gear being driven by a pinion 49, the shaft of which also carries a friction disk 50, with which co-operates, when it is desired to raise a load, another disk 51, carried by a longitudinally movable shaft 52, driven by a sprocket chain 53 from the motor.

Shaft 52 is shifted by a yoke engaged by a short lever 54, pivoted on frame member 4 and connected by a link 55 with an operating lever 56. Brake disk 48 is surrounded by a band 57, connected to another operating lever 58.

When a load is to be transported, the vehicle is run over the same and then the shoes 30 are engaged under the ends of boards on which the load is set. Then the shaft 52 is shifted to bring disks 50 and 51 into contact and, the motor being running, the load is hoisted to the desired height at which it is held by the brakes 48, 57. The truck is then driven to the place of delivery and the load is gradually lowered under control of said brake.

It will be seen that, in the form of the invention shown in Figs. 1 to 6, the vertical planes of the points of support of the load coincide with those of the wheel axes and, in the form shown in Fig. 7, the same is true with regard to the driving or traction wheels, and that the construction of the arched supporting members of I beams or similar structural shapes, provides a very strong yet simple frame, the legs of said beams forming very convenient and efficient guideways for the lifting shoes and for the rods which transmit the load to the wheels. It will also be obvious that the frame structure described can be embodied, in part or in whole, in any type of vehicle, for example, 55 in a trailer adapted to be attached to the rear end of an automobile, and that, therefore, my invention is not limited to the type of vehicle shown.

In Fig. 7 I have illustrated it, by way of example, in a truck in which the motor and driver's seat are at the front and not over the load. In this case, the spring suspension is omitted from the front arch member, which is secured to the horizontal longitudinal frame members 4 and 5 which are

connected to, or form part of, the chassis of the truck, the front end of which is supported in the usual way by springs on the front axle. If desired, only one arch member might be employed, in which case the lifting shelves 34 would extend farther longitudinally of the vehicle.

Having thus described my invention and its manner of use, what I claim is:

1. In a wheeled truck, the combination of longitudinal side frame members, transverse arched members the legs of which are secured to said side members, springs secured to said legs above the wheels, a strut between each spring and the corresponding wheel, and load supports carried on the inside of said legs.

2. In a truck, the combination with the wheels and lateral frame members, of vertical arched frame members the legs of which are secured to said lateral members, the center planes of said arched members intersecting the wheel axes, bearings and springs secured to the outside of said legs, struts guided in said bearings and engaging said springs at their upper ends and the wheel spindles at their lower ends, and load carrying means slidably mounted on the inside of said legs.

3. In a truck, a frame adapted to straddle the load and comprising an arched I beam, a wheel on the outside of each leg of said beam, a spring secured on the outside of each leg above said wheel, a strut between each spring and the corresponding wheel, guide bearings for said struts mounted on the outside of said legs, and load carrying means slidably mounted on the inside of said legs.

4. In a truck, the combination of a pair of longitudinal side frame members, a vertical arched beam connecting said members, a pair of steerable wheels at the front end of said members, a wheel on the outside of each leg of said beam, a spring secured to each leg, and a supporting member between said spring and said wheel.

5. A motor truck adapted to straddle the load to be conveyed, the frame of which comprises an arched beam of inverted U shape and longitudinal side members, steerable wheels supporting the front ends of said side members, a driving wheel opposite each leg of said beam, a yielding connection between said wheel and said leg, load carrying means slidably mounted on the inside of each leg, a motor on the frame, and connections therefrom whereby the driving wheels and the load carrying means are actuated.

6. In a truck, the combination of a pair of longitudinal side frame members, a pair of vertical arched transverse frame members connecting said side members, load carrying means slidably guided on the inside of the legs of said transverse members, thrust rods slidably guided on the outside of said legs,

wheel spindles carried by said rods, abutments on the upper ends of said legs, springs between said abutments and said rods, and means to raise and lower said load carrying means.

7. In a truck, the combination of side frame members, a front and a rear transverse frame member composed of an arched beam with its legs rigidly secured to said side members, bearings on the outside of said legs, rods carrying the wheel spindles mounted in said bearings, means to prevent the rods carrying the rear wheel spindles from turning in their bearings, springs bearing on the tops of the rods, abutments for said springs secured to said legs, load carrying shoes slidably mounted on the inside

of said legs, and means to raise and lower said shoes.

8. A truck adapted to be run over the load to be lifted, comprising an inverted U-shaped frame composed of arched beams connected by longitudinal side members, wheel carrying members slidably mounted on the outside of the legs of said beams, springs between the latter and said wheel carrying members, load carrying means slidably mounted on the inside of said legs, and means to raise and lower said load carrying means.

In testimony whereof I have hereunto set my hand.

WILLIAM S. OVERLIN.
